KNIFE SHARPNESS TESTER

Ethan W. Vars, Duncannon, Pa., assignor, by
mesne assignments, to The Aldon Products
Company, Duncannon, Pa., a corporation of
Pennsylvania

Application September 8, 1947, Serial No. 772,762

14 Claims. (Cl. 73—104)

This invention relates to a knife sharpness tester, and more particularly pertains to one for testing the sharpness of a straight-blade type of carving or slicing knife, by causing a piece of paper to be drawn transversely edgewise along the cutting edge and downwardly thereonto.

The device tests the sharpness of the cutting edge of a knife blade by causing a piece of paper to be drawn edgewise along the length of the cutting edge, with a determined weight or force, forcing the paper downwardly toward said cutting edge, the depth of cut in the paper being a measure of knife-sharpness. The device is adjustable so that a standard condition prevails throughout a series of tests with the same or different knives, whereby the depth of cut produced by a knife as compared to the depth of cut produced by itself before sharpening, or by another knife taken as a standard, measures the sharpness.

Therefore, it is an object of my invention to provide means for testing one or a plurality of knives, under standard conditions, measuring the sharpness by the depth of cut made in a piece of paper presented thereto in the testing operation.

Another object of my invention is to provide a knife sharpness tester device in which a piece of paper is drawn transversely edgewise along and down onto the cutting edge of the knife supported for test.

Another object of the invention is to provide adjustable testing condition means for such a testing device.

Further objects, and objects relating to details of construction and economies of operation, will definitely appear from the detailed description to follow. In one instance, I have accomplished the objects of my invention by the devices and means set forth in the following specification. My invention is clearly defined and pointed out in the appended claims. A structure constituting a preferred embodiment of my invention is illustrated in the accompanying drawings, forming a part of this specification, in which:

Fig. 1 is a side elevation of the device shown in the tilted operative position, particularly showing the slide rod and paper clamp mounting.

Fig. 2 is a plan view of the substance of Fig. 1.

Fig. 3 is a sectional view of part of the substance of Fig. 1, on the line 3—3 thereof.

Fig. 4 is a sectional view taken on the line 4—4 of Fig. 1.

Fig. 5 is a sectional view on the line 5—5 of Fig. 1, with parts broken away, and showing a piece of paper held in the clamp.

Fig. 6 is a section through the paper clamp, on the line 6—6 of Fig. 2.

Fig. 7 is a perspective view of the device at the beginning of an operation with the paper in contact with the rear end of the cutting edge of the knife.

In the drawings the sectional views are taken on the section lines looking in the direction of the arrows.

Referring to the drawings, I provide a base platform 20, upright support posts 21 and 22, spaced apart at opposite ends of the platform, and having supported therebetween a slide rod 23, and beneath it a stop supporting slide rod 24 on which are mounted stops 25 and 26, adjustably positioned lengthwise thereon and held by means of set screws 27 and 28, respectively.

A slidable mounting 29 has a tubular aperture 30 through which slide rod 23 passes, so that said mounting 29, unless otherwise restrained, may slide on rod 23 between posts 21 and 22. Depending from slidable mounting 29 is a fork 31 which straddles the stop slide rod 24, and the adjusted positions of stops 25 and 26, between which the fork is positioned, to determine the limits between which the slidable mounting can move along rod 23.

Projecting upwardly from mounting 29, is a bearing portion 32 (Fig. 5) having a tubular aperture 33, whose axis is transverse to the rod 23 and substantially horizontal, said aperture 33 rotatably receiving a shaft 34 which has secured to one end thereof an L-shaped support 35 (Fig. 2), from which extends a rod 36, threaded on its outer end, to receive a counterweight 37 adjustably screwed thereon. Extending in the other direction from the L-shaped support 35, is a balance rod 38, having slidably mounted thereon a balance weight 39, which may be slidably adjusted on the balance rod 38 and secured thereto by means of a set screw 40. As will be later explained, the counterweight 37 is normally set to balance rotating forces acting on shaft 34, to prevent its rotating, and the adjustment of balance weight 39 may be made along the scale 41, inscribed on balance rod 38, to provide an adjusted turning force for shaft 34.

Secured to the other end of shaft 34 is paper clamp holding yoke 42 (Fig. 6) having bent-over ears 43 and 44, through which runs a hinge pin 45. Hinged on pin 45, between the ears 43 and 44 of yoke 42 is an inner paper clamp plate 46 having bent-over flanges 47 and 48 pierced to receive pin 45, and an outer paper clamp plate 55 49 having bent-over flanges 50 and 51, through

which pin 45 passes. The clamping plates 46 and 49, at the hinged ends thereof, are spaced slightly apart, but extend outwardly and toward each other to end in a curved beak portion 52 (Figs. 5 and 7). A piece of paper, such as strip paper commonly used in adding machines, may be inserted between the plates 46 and 49, when they are separated, and when the plates are moved together the extending portion of the paper will be positioned as is portion 53 (Fig. 7).

To facilitate insertion and removal of paper strips from the paper clamp, and to secure them in place after insertion, I provide on plate 49, ears 54 and 55 (Fig. 5) through which a pin 56 is passed, the upper end of said pin 56 terminating in a handle 57. Mounted on the upper end of pin 56 by a collar 58 is a cam 59 having a cam slot 60 (Fig. 2) in which rides a pin 61 which passes through the flanges 47 and 48 of the inner paper clamp plate 46, extending therebeneath to pass through a similar slot in a cam 65 (Fig. 5) also secured by a collar 63 to pin 56. Suitable apertures are provided in flanges 50 and 51 of outer clamp plate 49 to accommodate the pin 61 when the plates are in closed position as shown in Fig. 2. To open the plates, to receive paper, the handle of pin 56 is turned, turning pin 56 and cams 59 and 62 in a counterclockwise direction as seen in Fig. 2, forcing the plates apart so that paper may be inserted through the beak 52, which is then opened. The handle 57 is then turned in the opposite direction to close the paper clamp. On each operation of the testing device, the paper clamp is opened and the strip of paper is pulled outward slightly to present a new portion thereof for test purposes.

The weight of the paper clamp, tending to rock shaft 34, is counterbalanced by adjustment of counterweight 37 on rod 36, with balance weight 39 in the position shown in Fig. 1. To provide a weight-bias, tending to cause the paper-holding beak end of the paper clamp to move downwardly with a calculated force, the balance weight 39 is moved along the scale to a point where such weight-bias is had and it is then clamped in place by set screw 40.

It will be perceived that, if the slide 29 is moved toward the stop 26, by means of handle 78 (Fig. 1), and the left end of the platform, as seen in Fig. 1 is elevated, as therein shown, the slide 29 will move down along rod 23 until the fork 31 stops against stop 25. If the paper clamp has been rocked upwardly by the operator, before the sliding motion occurs, the paper clamp will have both a rectilinear sliding motion and a rocking motion, downward, with a force selected by the adjustment of the balance weight.

To provide the proper tilting of the platform base 20, which preferably, should be approximately 30°, I provide a yoke-like leg or brace 71 hinged to the platform as at 72 and 73, which leg is held, releasably secured, by a bead chain 74 in the position shown in Fig. 7 by means of hook 72a. Between operations, the chain 74 may be released and the platform allowed to assume a horizontal position.

Referring especially to Figs. 4 and 7, I provide a knife support comprising a supporting post 80 secured to base 20 by means of screw bolt 81, said post being hollow and receiving the pin 82 of an anvil 83 provided with an arm 84 through which passes an adjusting screw 85 to position a clamp member 86 toward and away from the face 87 of said anvil 83, whereby a knife blade 88 may be clamped therebetween, cutting edge upward, and

extending outwardly from said anvil in a plane parallel to the plane of slide of the paper clamp. Set screw 89 provided in post 80 cooperates with neck portion 90 of pin 82, so the anvil, and consequently the direction of alignment of blade 88, may be adjusted around the vertical axis to make the knife blade axis extend in the direction of slide movement of the paper-holding equipment, so there will be no cross-sliding action of the paper relative to the cutting edge of the knife. The extended knife blade may be pointed upward slightly, if desired, as shown in Fig. 7, to attain a greater relative cutting action of the knife blade through the paper as the sliding motion occurs.

It will be apparent, from looking at Fig. 7, that, as the paper clamp slides lengthwise with respect to the knife blade and also rocks downwardly, the projecting portion 53 of the paper strip, is caused to move in transverse edgewise relationship along the length of the cutting edge of the knife and is forced downwardly thereonto, the depth of cut of the knife into the paper being a measure of the sharpness of the knife. By testing a series of knives under the same balanced weight-bias condition, the relative sharpness of them may be secured or by testing a knife during various stages of sharpening its improvement may be noted.

The fact that the curved beak 52 holds the projecting portion 53 of the paper supported along the direction of cut in the paper, a uniform cutting resistance in the paper is secured.

In operation, the platform base is adjusted to the tilting angle by means of the yoke-like brace 71 and the knife to be tested is secured in the knife clamp against the anvil 83 by means of the set screw 85, and the position of the knife around the vertical axis is adjusted by means of set screw 89. The paper clamp is then opened and a piece of paper is inserted between the plates of the clamp and the clamp is then closed, leaving projecting from the beak a portion of the paper. The balance weight 39 is then adjusted to the selected place on the scale, the operator holds the slide against the stop 26, at the same time rocking the paper clamp to the position shown in Fig. 7, whereupon the operator releases the paper clamp and the sliding and rocking movement thereof causes the knife blade cutting edge 90 to cut edgewise up into the protruding end of the paper to a depth determined by the sharpness of the knife. As the paper moves along the knife edge, the rocking down of the paper clamp will not take place until the knife cuts the paper. The arrows on the perspective view of the device (Fig. 7), show the direction of movement of the elements as the operation of testing proceeds.

I am aware that the machine described and illustrated herein may be varied considerably without departing from the spirit of my invention, and, therefore, I claim my invention broadly, as indicated by the appended claims.

Having thus described my invention, what I claim as new and useful and desire to secure by Letters Patent is:

1. In a knife sharpness tester, in combination, a platform base; means attached to the base which is adjustable to tilt it from a normal horizontal position so that one end is raised; a slide rod supported by the base and extending above and along it in lengthwise direction; a knife support mounted on said base for holding a knife blade, cutting edge up, extending alongside the slide rod; a mounting slidably mounted on the slide rod so that when positioned near the up-

ward end of the rod, when tilted, it will slide toward the lower end; a paper clamp rockably mounted in the slidable mounting so as to rock around a horizontal axis normal to the slide rod, said clamp being adapted to hold a piece of paper edgewise across the vertical plane in which a supported knife blade lies, said paper clamp being weight-biased so as to tend to rock the held paper downwardly across the knife blade cutting edge, whereby, when the base is tilted, the paper clamp rocked upwardly so the lower edge of the paper lies above and across the cutting edge of the knife, and the mounting and paper clamp are slid by an operator to the upper end of the rod and released, the combined sliding and rocking movement, given the paper, causes the paper to move in edgewise cutting relation downwardly and along the length of the blade, the depth of the cut in the paper being a measure of the sharpness of the cutting edge of the blade.

2. In a knife sharpness tester, in combination, a platform base; means attached to the base which is adjustable to tilt it from a normal horizontal position so that one end is raised; a slide rod supported by the base and extending above and along it in lengthwise direction; a knife support mounted on said base for holding a knife blade, cutting edge up, extending along the slide rod; a mounting slidably mounted on the slide rod so that when positioned near the upward end of the rod, when tilted, it will slide toward the lower end; an upper stop and a lower stop, mounted on the platform base, between which the slidable mounting may move; a paper clamp rockably mounted in the slidable mounting so as to rock around a horizontal axis normal to the slide rod, said clamp being adapted to hold a piece of paper edgewise across the vertical plane in which the supported knife blade lies, said paper clamp being weight-biased so as to tend to rock the held paper downwardly across the knife blade cutting edge, whereby, when the base is tilted, the paper clamp rocked upwardly so the lower edge of the paper lies above and across the cutting edge of the knife, and the mounting and paper clamp are slid by an operator to the upper end of the rod and released, the combined sliding and rocking movement given the paper, causes the paper to move in edgewise cutting relation downwardly and along the length of the blade, the depth of cut in the paper being a measure of the sharpness of the cutting edge of the blade.

3. The device of claim 2 in which the weight-bias of the paper clamp comprises an adjustable counterweight, adjustment of which determines the force with which the paper is rocked downwardly onto the knife cutting edge.

4. The device of claim 1 in which the weight-bias of the paper clamp comprises an adjustable counterweight, adjustment of which determines the force with which the paper is rocked downwardly onto the knife cutting edge.

5. The device of claim 1 in which the paper clamp consists of two flat plates hinged at one end together, the other ends of said plates being curved into a beak, and in which the paper is held between said plates and extending outwardly from said beak.

6. A knife sharpness tester, including, in combination, knife support means for holding a knife blade extended, cutting edge up; paper-holding means pivotably mounted on a slidable supporting means mounted alongside the knife support means, said paper-holding means holding a piece

of paper edgewise across the plane of the knife blade, and weight-biasing means acting upon the paper-holding means so that when the paper holding means slides, the held paper is moved edgewise downwardly and along the knife cutting edge.

7. A knife sharpness tester, including, in combination, knife support means for holding a knife blade extended, cutting edge up; rockable paper-holding means slidably mounted alongside the knife support means, said paper-holding means holding a piece of paper edgewise across the plane of the knife blade, and weight-biased means for rocking the paper-holding means so that when the paper holding means slides and rocks, the held paper is moved edgewise downwardly and along the knife cutting edge.

8. A knife sharpness tester, including, in combination, a base; a knife holder secured to the base, said holder being adapted to receive and hold a knife with its blade extending outwardly therefrom, edge up; a paper clamp pivotably mounted on a slidable member secured to the base, said clamp being adapted to hold a strip of paper so it extends in a plane crossing the plane of the knife blade and weight-biased means for turning the paper clamp so that sliding movement of the paper clamp causes the paper to move along the length of the blade so the knife edge will make edge-cutting contact with the paper as the paper moves along the length of the blade edge.

9. A knife sharpness tester, including, in combination, a base; a knife holder secured to the base, said holder being adapted to receive and hold a knife with its blade extending outwardly therefrom, edge up; a slide mounted on the base substantially parallel to the blade of a held knife; a mounting slidably mounted on the slide; a paper clamp rockably mounted on a horizontal shaft rotatable in the mounting, and means for yieldably rocking the paper clamp, said paper clamp being adapted to hold a strip of paper so when the clamp is rocked the paper extends edgewise across and above the knife edge, said slide and said rockable mounting being so located with respect to the knife blade held in the knife holder, that the sliding movement of the mounting carrying the paper clamp and the downward rocking movement of the clamp, causes the paper to move downwardly toward and along the length of the blade so the knife edge will make edge-cutting contact with the paper as the paper moves along the length of the blade edge, the rockable mounting of the paper holder being biased to rock downwardly.

10. In a knife sharpness tester, in combination, a base; a support for holding a knife with the blade extended and the cutting edge pointed upwardly, and said knife support being secured to said base; a paper clamp slidably mounted on a slide member secured to the base and provided with two plates forming a beak portion gripping the paper, said clamp being rockable upwardly and downwardly in its mounting and being adapted to hold a strip of paper so when it is rocked upwardly the paper extends edgewise across and above the knife edge, so that sliding movement of the paper clamp causes the paper to move along the length of the blade so the knife edge will make edge-cutting contact with the paper, as the paper moves along the length of the blade's edge, and so that rocking downwardly thereof causes a cutting of the blade into the

paper, said clamp supporting said paper in the beak portion close to the line of cut.

11. A knife sharpness tester, including, in combination, a platform base; a slide rod mounted on and extending between standards which extend upwardly from the base; a mounting slidably mounted on the slide rod, between limits; a paper clamp rockably carried by the mounting so the clamp will rock on a horizontal axis transverse of the slide rod, said paper clamp being weight-biased by means associated therewith to rock downwardly around the axis when first rocked up; a knife holder for holding a knife with the blade cutting edge upward and extending therefrom parallel to the slide rod, said elements being so positioned with respect to each other that a piece of paper carried by the clamp, when the clamp is rocked upwardly, extends edgeways across and above the knife edge when the mounting is slid to its limit at one end of the slide rod, so that sliding movement of the mounting to the other end of the slide rod will carry the paper held in the clamp along the knife edgeways, and so the weight-bias of the paper clamp will, during such sliding motion, cause the paper to move into slicing contact with the knife blade cutting edge, along its length.

12. A knife sharpness tester, including, in combination, a platform base; a slide rod mounted on and extending between standards which extend upwardly from the base; a mounting slidably mounted on the slide rod; limiting means defining the length of the sliding movement of the mounting on the rod; a paper clamp rockably carried by the mounting so the clamp will rock up and down on a horizontal axis transverse of the slide rod, said paper clamp being weight-biased by means associated with the clamp so as to rock downwardly around the axis when, first, it has been rocked upwardly; a knife holder for holding a knife with the blade cutting edge upward and extending therefrom parallel to the slide rod, said elements being so positioned with respect to each other that a piece of paper carried by the clamp, when the clamp is rocked upwardly, extends edgeways across and above the knife edge when the mounting is slid to its limit at one end of the slide rod, so that sliding movement of the mounting to the other limit on the slide rod will carry the paper held in the clamp along the knife edge, edgeways, and so the weight-bias of the paper clamp will, during such sliding motion, cause the paper to move into slicing contact with the knife blade cutting edge, along its length.

13. A knife sharpness tester, including, in combination, a platform base; a slide rod mounted on and extending between standards which extend upwardly from the base; a mounting slid-

ably mounted on the slide rod; limiting means defining the limits of motion of the mounting on the slide rod; a paper clamp rockably carried by the mounting so the clamp will rock up and down around a horizontal axis transverse of the slide rod, said paper clamp being biased so as to rock downwardly around the axis; a weight-biased means for holding the paper clamp, a knife holder for holding a knife with the blade cutting edge upward and extending therefrom, parallel to the slide rod, said elements being so positioned with respect to each other that a piece of paper carried by the clamp, when the clamp is rocked upwardly, extends edgeways across and above the knife edge, when the mounting is slid to its limit at one end of the slide rod, so that sliding movement of the mounting, caused by elevation of that end of the platform from which the sliding movement is to be made, causes the mounting to slide to the other limit on the slide rod so as to carry the paper held in the clamp along the knife blade cutting edge, edgeways, and so the paper clamp will, by its downward rocking, during such sliding movement, cause the paper to move into slicing contact with the knife blade cutting edge along its length, the depth of cut made in the paper being indicative of the sharpness of the knife.

14. A knife sharpness tester, including, in combination, a knife support means for holding a knife blade, cutting edge up, a paper-holding means mounted on a rotatable shaft alongside the knife support means in position to hold a piece of paper edgeways across the plane of the knife blade, a weight-biased means holding the paper against the knife blade and means for permitting relative movement, longitudinally of the knife edge, between the paper-holding means and the knife support means so that the paper is moved edgewise downwardly on the knife cutting edge as the knife support and paper-holding means move relatively.
